SPREADER TOOL FOR ADJUSTING CAMBER AND CASTER OF VEHICLE WHEELS

John Melvin Johnson, 417 2nd St., Lindsborg, Kans.

Filed Jan. 5, 1960, Ser. No. 58,940

Term of patent 3½ years

(Cl. D54—13)

Figure 1 is a perspective view of the spreader tool for adjusting camber and caster of vehicle wheels, showing my new design.

Figure 2 is a top plan view thereof.

Figure 3 is a sectional view taken substantially along the line 3—3 of Figure 2 as viewed in the direction of the arrows.

Figure 4 is a sectional view taken substantially along the line 4—4 of Figure 1 as viewed in the direction of the arrows.

I claim:

The ornamental design for a spreader tool for adjusting camber and caster of vehicle wheels, as shown.
